UNITED STATES PATENT OFFICE

JAMES F. LOUCKS, OF CLEVELAND, OHIO, ASSIGNOR TO DETROIT STEEL PRODUCTS COMPANY, OF DETROIT, MICHIGAN, A CORPORATION OF MICHIGAN

CLAMPING DEVICE FOR BUILDING FOUNDATIONS

Application filed August 11, 1930. Serial No. 474,498.

This invention relates to the means for securing to supporting beams sheet metal foundations having supporting ribs extending from one side thereof and, in the embodiment shown herein, is particularly well adapted for use with the triangular hollow ribs of foundations of the general type shown in the patent granted jointly to Harry Gillett and myself on February 3, 1926, No. 1,574,586.

It is the general purpose and object of the invention to provide a clamping device which is simple in construction and economical of production; which is adapted for ready and convenient application to the ribs of such sheet metal foundations; and which will effectively support such foundations from the beams or purlins.

I realize the foregoing objects, and other and more limited objects which will appear hereinafter, in and through the construction and arrangement of parts shown in the drawings, wherein Fig. 1 represents a detail in transverse section through one form of sheet metal foundation showing the manner in which such foundation is clamped or applied to a beam or purlin by means of my clamping devices; Fig. 2 is a detail in plan showing the manner of applying one of my clamping devices to the top of a beam or purlin; Fig. 3 a detail in transverse section showing the positions of the bottom of a rib and of the clamping device prior to the final clamping operation; Fig. 4 is a view, similar to Fig. 3, showing the clamping device in its final clamping position with reference to a rib; Fig. 5 a detail in section through an I-beam and the sheet metal foundation thereon, showing the manner in which the latter is secured to said beam by one of my devices; Fig. 6 a perspective view showing one of my devices prior to its application to a beam or purlin; and Fig. 7 a plan view of the blank from which one of my clamping devices is formed.

Figures 8, 9 and 10 are views similar respectively to Figures 5, 6 and 7 showing a modified construction.

Describing by reference characters the parts shown herein, 1 denotes a flat metal sheet from which the foundation is formed,

the sheet being provided with hollow triangular ribs projecting from one side thereof, the sides of the ribs being indicated at 2 and the bottoms at 3, there being slots 4 between the tops of the ribs and the body of the metal sheet.

5 denotes the web and 6 the flanges of a beam on which the sheet metal foundation is supported. The beam may be of any of the usual commercial shapes, the one shown herein being an I-beam. For the purpose of securing the foundation, either to an I-beam such as shown or to an angle beam, I provide a sheet metal clamp having a base 7 adapted to rest on top of a beam, the said base being provided intermediate of its ends with upwardly extending sides 8 and 9, each side having an inwardly directed flange 8^a, 9^a, respectively, at the top thereof. The side 9 is longer than the side 8, being provided with a forwardly extending portion 9^b which is not provided with a top flange, the flanges 8^a and 9^a being preferably co-extensive in length. The base is provided with a central longitudinal upwardly extending arch 10 pressed therefrom, said arch being shown as extending forwardly approximately to the front end of the side 8 and the flanged portion of the side 9. The base is extended rearwardly beyond the sides 8 and 9, as shown at 7^a and is provided with a central slot 7^b extending rearwardly from the end of the rib 10.

It is intended that the fastening device shall be applied to the narrow edge of a beam by means of a hook, and the hook shown herein forms an extension of a side member 11 which projects upwardly from the forward end of the base 7. The manner in which the hook is formed, as well as the other parts of the clamping device, will be explained in connection with Fig. 7, which shows the blank from which one of such devices is formed. The blank, indicated at A, is given an appropriate shape whereby on bending on the broken lines A' the sides 9, 9^b and 8 and 11 will be formed while, by further bending on the lines A^a, the flanges 8^a and 9^a will be formed. By cutting on the lines B, B' and B^a prior to the bending operation and

then bending the part 11 upwardly, the hook proper 12 will be formed, which hook will extend diagonally rearwardly from the side member 11, as will appear from Figs. 1, 2 and 6.

5 It will be noted that the sides 8 and 9 form each an obtuse angle with the plane of the base 7 and that the rear end of the side member 9^b also forms the same obtuse angle with the base as does the side member 9 but that this obtuse angle diminishes as the side member 9^b extends forwardly from the member 9 until, at its extreme forward end, the side member 9^b is substantially at right angles to the plane of the base.

10 With the parts constructed and arranged as described, the fastening devices are applied to the respective beams by hooking the front end of each device around the flange of such beam, in the manner shown, after 15 which the rear end 7^a is bent against or around the opposite edge of such beam, the position of such extension 7^a prior to such bending operation being shown in dot-and-dash lines in Fig. 2.

15 The over-all width of the base 7 of each clamping device is equal, or substantially equal, to the width of the base 3 of the rib which it receives. Having applied the clamping devices to the beams in the manner described and at the proper distances apart to receive therein the ribs, the ribs are inserted 20 into their respective clamping devices in the manner shown in Fig. 3. A suitable tool, indicated by dot-and-dash lines at 13, is introduced into each slot 4, with the bottom of 25 the tool engaging the bottom of the rib above the center of the arch or rib provided in the bottom of the clamp. By hammering or otherwise exerting downward pressure through 30 the tool upon the bottom of the rib and upon the arch 10, the base of the clamp will be straightened, as shown in Fig. 4 and, because 35 of the angles which the side members 8 and 9 make with the portion of the base adjacent thereto, the flanges 8^a and 9^a will be forced 40 into engagement with the sides 2 of the rib, preferably with such force as to slightly 45 indent such sides, as shown at 2^a. This 50 straightening or flattening of the arch 10 also results in moving the top of the side member 9^b inwardly a sufficient distance to 55 make the said member assume a position substantially vertical to the base.

60 The construction shown and described herein provides a cheap but extremely strong hook, due to the width of the web formed by the parts 11, 12 and 14. Furthermore, the vertical web formed by the side member 9^b at the immediate rear of the slot produced 65 at the forward end of the base in forming the hook 12 forms a reinforcement for the forward end of the clamping device, thereby contributing to the strength of the same.

65 The deflection of the lower end portion 12

of the hook toward the longitudinal center of the clamp prevents the clamp from tipping toward the side from which the hook projects when the clamp is applied to and driven upon the beam.

70 The modified construction shown in Figures 8, 9 and 10 is similar to that already described, with the exception that two hooks 75 11 and 11^a are formed on opposite sides of the blank A, being severed from the portions 8^b and 9^b by shearing along the lines B^a and B^b. The blank is folded or bent along the lines C and C' similar to the bend along the lines A' and A^b in Figure 7, and the structure in its normal form is shown in 80 Figure 9. The securing of this member to the supporting beam and the engagement and securing of the ribbed plate thereto is the same as that previously described but because of the pair of hooks 11 and 11^a upon 85 opposite sides, an additional element of security is provided.

Having thus described my invention, what I claim is:

1. A sheet metal clamping device for securing to a beam a sheet having a rib projecting therefrom, said clamping device having means whereby it may be applied to a beam and being provided with a base having an upwardly projecting portion and with upwardly projecting sides extending from such base and each having an inwardly projecting flange at its top adapted to engage a side of the rib when the upwardly projecting portion of the base shall have been straightened out or flattened down.

2. A sheet metal clamping device for securing to a beam a sheet having a rib projecting therefrom, said clamping device having means whereby it may be applied to a beam and being provided with a base having an upwardly projecting portion and with upwardly projecting sides extending from such base and each having a projection extending inwardly therefrom and adapted to engage a side of the rib when the upwardly projecting portion of the base shall have been straightened out or flattened down.

3. A sheet metal clamping device for securing to a beam a sheet having a rib projecting therefrom, the said clamping device comprising a base having a longitudinally extending upwardly arched portion and sides extending upwardly and outwardly from such arched portion of the base, each side having an inwardly extending projection, the sides and projections being so arranged that the sides will be forced inwardly by straightening or flattening down the arched portion of the base and the projections will be moved into engagement with opposite sides of such rib.

4. A sheet metal clamping device for securing to a beam a sheet having a rib projecting therefrom, the said clamping device com-

prising a base adapted to rest upon a beam and having sides adapted to engage the opposite sides of such rib, the said device having a hook adapted to engage the edge of such beam, the said hook comprising a vertical web extending longitudinally of said device and from one side of the said base, and a hook proper below said base and connected to the said web by a vertically extending web, the body of the hook being deflected rearwardly 5 and toward the side of the base which is opposite the first mentioned web and having its rear end adjacent to the longitudinal center of such base.

5. A sheet metal clamping device for securing to a beam a sheet having a rib projecting therefrom, the said clamping device comprising a base adapted to rest upon a beam and having sides adapted to engage the opposite sides of such rib, the said device 10 having a hook adapted to engage the edge of such beam, the said hook comprising a vertical web extending longitudinally of the said base, and a hook proper below said base and connected to the said web by a vertically extending web.

6. A sheet metal clamping device for securing to a beam a sheet having a rib projecting therefrom, the said clamping device comprising a base adapted to rest upon a beam and having sides adapted to engage the opposite sides of such rib, the said device having a hook adapted to engage the edge of such beam, the said hook comprising a web extending upwardly from one side of the said base and a hook proper below said base and connected to the said web by a vertically extending web, the body of the hook being deflected rearwardly and toward the side of the base which is opposite the first mentioned web and the forward end of the opposite side of said base being provided with a web projecting upwardly therefrom.

7. A clamping device for the purpose described comprising a sheet metal blank fashioned to form a central portion, side portions and opposite end portions, one of said end portions being sheared to form a return bent hook and being bent into a plane extending at right angles to the plane of the blank, said central portion being arched upward and said side portions being bent to extend upward at an obtuse angle to the original plane of the blank but at a smaller angle to said arched central portion and having inwardly extending flanges at their upper ends whereby said hooked portion and opposite end portion are adapted to engage the supporting beam for securing thereto and the flattening down of said arched portion will draw said side portions inward to embrace and clamp the member engaged therewith.

8. A sheet metal clamping device for securing to a beam a sheet having a rib projecting therefrom, the said device comprising

a base having a longitudinally extending upwardly arched portion and sides extending upwardly and outwardly from such arched portion of the base, each side having an inwardly extending projection, the sides and projections being so arranged that the sides will be forced inwardly by straightening or flattening down the arched portion of the base and the projections will be moved into engagement with opposite sides of such rib, 70 the said device being provided at one end thereof with hooks projecting downwardly from opposite sides of such end and the end of the base which is opposite the hooks extending beyond the sides and adapted to be 75 bent into engagement with the opposite edge of such beam.

9. A sheet metal clamping device for securing to a beam a sheet having a rib projecting therefrom, the said device comprising a base having a longitudinally extending upwardly arched portion and sides extending upwardly and outwardly from such arched portion of the base, each side having an inwardly extending projection, the sides and projections being so arranged that the sides will be forced inwardly by straightening or flattening down the arched portion of the base and the projections will be moved into engagement with opposite sides of such rib, 80 the said device being provided at one end thereof with hooks projecting downwardly from opposite sides of such end and the end of the base which is opposite the hooks extending beyond the sides and adapted to be 85 bent into engagement with the opposite edge of such beam.

10. A sheet metal clamping device for securing to a beam a sheet having a rib projecting therefrom, the said device comprising a base having a longitudinally extending upwardly arched portion and sides extending upwardly and outwardly from such arched portion of the base, each side having an inwardly extending projection, the sides and projections being so arranged that the sides will be forced inwardly by straightening or flattening down the arched portion of the base and the projections will be moved into engagement with opposite sides of such rib, 95 the said device being provided at one end thereof with hooks projecting downwardly from opposite sides of such end and the end of the base which is opposite the hooks extending beyond the sides and adapted to be 100 bent into engagement with the opposite edge of such beam.

11. A sheet metal clamping device for securing to a beam a sheet having ribs projecting therefrom, the said clamping device comprising a base having a centrally longitudinally extending upwardly arched portion and sides bent from such base and extending up- 125

wardly and outwardly from the arched portion of the base, each side having an inwardly extending projection, and hooks bent downwardly from opposite sides of the forward edge of such base and adapted to engage one edge of a beam, the said base extending rearwardly from the sides and providing an extension adapted to be bent into engagement with the opposite edge of such beam.

10 12. A sheet metal clamping device for securing to a beam, a sheet having a rib projecting therefrom, said clamping device having means whereby it may be applied to a beam and being provided with a base, members projecting therefrom having engaging portions and means on said base deformable to cause said members to engage and clamp said rib.

13. A sheet metal clamping device for securing to a beam, a sheet having a rib projecting therefrom, said clamping device having means whereby it may be applied to a beam and being provided with a base having laterally projecting side flanges, said flanges having engaging portions and means on said base deformable to cause said flanges to engage and clamp said rib.

14. A sheet metal clamping device for securing to a beam, a sheet having a rib projecting therefrom, said clamping device having means whereby it may be applied to a beam and being provided with a base having diverging side flanges, each flange having an inwardly extending flange across its top and means on said base deformable to cause said side flanges to engage and clamp said rib.

In testimony whereof I affix my signature.
JAMES F. LOUCKS.
